Primary Examiner — Jennifer L Watkins

(74) *Attorney, Agent, or Firm* — Finnegan, Henderson, Farabow, Garrett & Dunner LLP

(57) **CLAIM**

The ornamental design for footwear, as shown and described.

DESCRIPTION

FIG. 1 is a front right perspective view of the footwear showing my new design;

FIG. 2 is a top plan view thereof;

FIG. 3 is right side elevation view thereof;

FIG. 4 is a left side elevation view thereof;

FIG. 5 is a front elevation view thereof;

FIG. 6 is a back elevation view thereof; and,

FIG. 7 is a bottom plan view thereof.

The broken lines of uneven length represent the boundary of the claimed design and form no part of the claimed design.

1 Claim, 7 Drawing Sheets
